CLAIM

We claim the ornamental design for an angled mounting bracket, as shown and described.

DESCRIPTION

FIG. 1 is a perspective view of an angled mounting bracket mounted on a license plate mounting bar of a motorcycle showing our new design, including a cut-away view of the license plate and a cut-away view of the license plate mounting bar shown for purposes of illustration;

FIG. 2 is a perspective view of an angled mounting bracket of the present invention;

FIG. 3 is a right side elevation view of an angled mounting bracket of FIG. 2, the left side elevation view a mirror image of the right side elevation view;

FIG. 4 is a front elevation view of the angled mounted bracket of FIG. 2;

FIG. 5 is a rear elevation view of the angled mounting bracket of FIG. 2;

FIG. 6 is a bottom plan view of an angled mounting bracket of FIG. 2; and,

FIG. 7 is a top plan view of the angled mounting bracket of FIG. 2.

The broken lines shown are for illustrative purposes only and form no part of the claimed design.
